UNITED STATES PATENT OFFICE

WILLIAM ADDINGTON AND CHARLES G. ADDINGTON, OF REDWING, COLORADO

ADJUSTABLE HEADREST FOR MORTICIANS

Application filed May 19, 1930. Serial No. 453,706.

The present invention relates to a head rest particularly designed for use by morticians in order that they may perform their duties more efficiently and more easily.

5 The objects of the invention are to provide a head rest of this nature which is adjustable, easy to manipulate, thoroughly efficient and reliable in use and operation, strong and durable, inexpensive to manufacture, and 10 otherwise well adapted to the purpose for which it is designed.

With the above and numerous other objects in view as will appear as the description proceeds, the invention resides in certain 15 novel features of construction, and in the combination and arrangement of parts as will be hereinafter more fully described and claimed.

20 In the drawings:

Figure 1 is a side elevation of a head rest embodying the features of our invention,

Figure 2 is an end elevation thereof,

Figure 3 is a fragmentary vertical section taken substantially on the line 3-3 of Figure 2,

Figure 4 is a longitudinal vertical section, Figure 5 is a top plan view,

Figure 6 is a vertical longitudinal section 30 showing the inner portions in elevation,

Figure 7 is a bottom plan view,

Figure 8 is a perspective view of one of the pins, and

Figure 9 is a fragmentary detail view of 35 the lower end of one of the rocker members.

Referring to the drawings in detail it will be seen that numerals 5 and 6 denote box like sections, the latter of which is slidable over the former. The box like structure 5 comprises end walls 7, side walls 8, a top 9, and an inwardly directed bottom flange structure 10. The end walls 7 are provided with a series of openings 11. The top wall 9 has its central position arcuated downwardly as is indicated at 12.

40 Feet 14 are mounted on the corner portions of the flange structure 10 to depend downwardly. The outer and upper section 6 includes end walls 15, side walls 16, top 17 and bottom outwardly directed flange structure 18.

The top 17 is provided with the downwardly arcuated central portion 19. Bolts 20 depend from the end portions of the top 17 to extend through openings in the top 9 and on the lower ends of these bolts or rods 20 there are stop nuts 21 thus limiting the upward movement of the section 6 from the section 5.

55 Rocker elements R are rockably mounted on the outer sides of end walls 15 by having flanges 23 with pins 24 extending therebetween and rockable in ears 25 projecting outwardly from the end walls 15 clearly shown in Figure 3. Springs 27 cooperate with the rockable element so as to hold their bottom ends inwardly and in these bottom ends are pins 28 having reduced shanks 29 extending through slots 30 in the lower ends of the rocker elements and held in place by nuts 31.

60 These pins are slidable through openings 32 in the end walls 7 so as to project through openings 11 so as to hold the sections 6 at different elevations in respect to the section 5.

65 From the above detailed description it will be seen that we have devised an adjustable head rest which may be constructed of sheet metal or any other like suitable material so as to be made strong and durable, capable of being easily cleansed, sterilized and otherwise maintained in a sanitary condition. It will further be seen that the apparatus is 70 easy to manipulate and thoroughly efficient and adapted for the purpose intended.

75 Of course the present embodiment of the invention has been disclosed in considerable detail merely for the purpose of exemplification since in actual practice it attains the features of advantage enumerated as desirable in the statement of the invention and the 80 above description.

85 It will be apparent that changes in the details of construction, and in the combination and arrangement of parts may be resorted to without departing from the spirit 90 or scope of the invention as hereinafter claimed or sacrificing any of its advantages.

Having thus described our invention, what 95 we claim as new is:

1. A head rest of the class described com-

prising a pair of box like sections one slideable over the other, said one section having its bottom end open to receive said other section, and means for holding said one section in different adjusted positions in respect to said other section, the top of said one section having its central portion arcuated downwardly, the top wall of said other section having its central portion similarly arcuated 10 downwardly for the reception of the arcuated portion of said one section.

2. A head rest of the class described comprising a pair of box like sections one slideable over the other, said one section having its bottom end open to receive said other section, and means for holding said one section in different adjusted positions in respect to said other section, the top of said one section having its central portion arcuated downwardly, 15 the top wall of said other section having its central portion similarly arcuated downwardly, a bolt depending from the top wall of said one section through openings in the top of the other section, and means on the 20 bottom ends of the bolt to limit the upward movement of said one section from said other section.

3. A head rest of the class described comprising a pair of box like sections one slideable over the other, said one section having its bottom end open to receive said other section, and means for holding said one section in different adjusted positions in respect to said other section, the top of said 30 one section having its central portion arcuated downwardly, the top wall of said other section having its central portion similarly arcuated downwardly, a bolt depending from the top wall of said one section 35 through openings in the top of the other section, and means on the bottom ends of the bolt to limit the upward movement of said one section from said other section, rockers mounted on the ends of said one section 40 and having pins insertable in a plurality of openings in the end walls of said other section.

In testimony whereof we affix our signatures.

60 WILLIAM ADDINGTON.
CHARLES G. ADDINGTON.
